UNITED STATES PATENT OFFICE

ARTHUR H. ROBINSON, OF LAKEWOOD, OHIO, ASSIGNOR TO THE A. H. ROBINSON COMPANY, OF MASSILLON, OHIO, A CORPORATION OF OHIO

AIR FAN

Application filed December 3, 1928. Serial No. 323,437.

My invention relates to air fans, mounted on a portable base and operating in a duct, and adapted for increasing the circulation of air from hot air registers, or into the cold air shafts of a hot air furnace.

The objects of the present improvements are to provide an air fan of this description, which may be applied either to horizontal or vertical registers, which is constructed in 10 a simple and compact manner, and in which vibration is not imparted from the fan to the duct and base.

These and ancillary objects are attained in the present improvements as will herein- 15 after be set forth in detail and claimed.

A preferred embodiment of the improvements is illustrated in the accompanying drawings forming part hereof, in which

Figure 1 is a fragmentary isometric view 20 of the improved air fan;

Fig. 2, a top plan view thereof;

Fig. 3, a front elevation view thereof;

Fig. 4, a fragmentary diagrammatic view 25 illustrating the fan in use with a vertical hot air register;

Fig. 5, a fragmentary diagrammatic view illustrating the fan in use with a horizontal hot air register; and

Fig. 6, a fragmentary diagrammatic view 30 illustrating the fan in use with a cold air register.

Similar numerals refer to similar parts throughout the several views.

The improved air fan indicated generally 35 at 10 includes fan blades 11 mounted upon a shaft 12 and propelled by a motor 13, which is preferably an electric motor adapted for operation by connection as by means of a cord 14 with an electric light circuit.

A combined fan blade guard and motor 40 mounting frame indicated generally at 15 encloses the fan blades and mounts the motor.

The frame 15 is itself mounted on a base indicated generally at 16, and which is adapted for resting upon a flat surface to maintain the shaft either horizontal as illustrated in Fig. 4, or vertical as illustrated in Figs. 5 and 6.

The base 16 preferably comprises a duct 50 17 coaxial with the motor and within which

the frame 15 is secured as by means of clamps 18.

The duct 17 is preferably in the form of a cylindric tube, and the frame 15 preferably includes a plurality of longitudinally extending circumferentially spaced outer members 19 upon each of which a bushing of resilient material 20 is applied, and which may be felt, insulating tape, or rubber tubing, for the purpose of absorbing vibrations in the 55 frame set up by the operation of the fan and which would otherwise cause a hum due to the sounding-board action of the tubular duct 17.

In addition to the tubular duct 17, the base 16 includes longitudinally spaced supporting feet 21 having parallel outer edges 22 arranged to rest upon the surface of the floor 23 or the like for maintaining the fan shaft horizontal; and either end of the duct 17 is preferably finished so that its plane is 60 perpendicular with the shaft 12 whereby the fan may be supported thereon for maintaining the shaft vertical.

As illustrated in Fig. 4 the shaft is maintained horizontal for use in connection with 75 a vertical hot air register 24, and the fan blades are positioned to increase the velocity of the flow of hot air out of the register as indicated by the arrows.

In Fig. 5 the fan is in use with a horizontal 80 hot air register 25 with the shaft maintained vertical and the fan blades positioned to increase the velocity of the flow of hot air out of the horizontal hot air register.

In Fig. 6 the shaft is similarly maintained 85 vertical and the fan blades are positioned opposite to that shown in Fig. 5, whereby an increased velocity of air flow into the cold air register 26 is induced.

Accordingly one of the improved portable 90 fans embodying the present improvements may be utilized in any desired hot air register or cold air register in a hot air heating system for increasing the air flow therefrom or therein.

I claim:

1. An air fan including fan blades, rotary means for operating the blades to induce a flow of air, guard means connected with the operating means surrounding the blades, a 100

- tubular duct coaxial with the operating means and open at both ends, means connecting the periphery of the guard means with the tubular duct intermediate the ends of the duct, and means extending from the tubular duct having surfaces parallel with and perpendicular to the axis of the operating means, whereby the fan is adapted to be supported on either of said surfaces for selectively positioning the blades to induce a horizontal or a vertical flow of air.
2. An air fan including fan blades, rotary means for operating the blades to induce a flow of air, guard means connected with the operating means surrounding the blades, a tubular duct coaxial with and surrounding the operating means, means connecting the periphery of the guard means with the tubular duct intermediate the ends of the duct, vibration absorbing means at the connection between the guard means and tubular duct for absorbing vibrations set up by the operating means, and means extending from the tubular duct having surfaces parallel with and perpendicular to the axis of the operating means, whereby the fan is adapted to be supported on either of said surfaces for selectively positioning the blades to induce a horizontal or a vertical flow of air.
3. An air fan including fan blades, means for operating the blades to induce a flow of air, guard means surrounding the blades and connected with the operating means, means supporting the guard means, the supporting means including a tubular member encircling and extending over the guard means and the operating means, resilient bushings spaced at intervals around the periphery of the guard means, and brackets on the tubular member clamped around said bushings resiliently connecting the guard means to the supporting means.

In testimony that I claim the above, I have hereunto subscribed my name.

ARTHUR H. ROBINSON.
